UNITED STATES PATENT OFFICE

2,608,439

LIQUID SPRAY DEVICE

Ernest N. Bates and Rex V. Bates, Detroit, Mich.

Application April 1, 1949, Serial No. 84,838

10 Claims. (Cl. 299—84)

1

This invention relates to portable chemical mixing and dispensing units of the type usable as washing and scrubbing equipment, spraying equipment, and the like.

The primary object of the invention is to provide improved means for mixing soaps, detergents and other chemicals with water as supplied under pressure, dispersing the soap, detergents or other chemical in aqueous solution, and dispensing the resultant solution alone or with clear water at the option of the user in such varied proportions as may be selected by the user.

The invention is disclosed in the form of a chemical dispensing and washing unit particularly usable as an automobile washer; however, it is obvious that the washer may be for other purposes such as washing down buildings, boats and the like, scrubbing floors, and for many other purposes where varied aqueous soap and detergent solutions are desired or required. Also, by substituting a spray nozzle for the brush element, the invention may be used as a sprayer or fertilizer spreader when charged with dissolvable crystal or powdered insecticides or fertilizer.

Other objects of the invention will become apparent by reference to the following detailed description taken in connection with the accompanying drawings, in which:

Fig. 1 is a front elevational view of a chemical dispensing and washing unit embodying the invention.

Fig. 2 is a side elevational view taken from the left hand side of the chemical dispensing and washing unit as shown in Fig. 1.

Fig. 3 is a top plan view.

Fig. 4 is an enlarged vertical sectional view taken on the line 4—4 of Fig. 2.

Fig. 5 is an enlarged fragmentary vertical sectional view through the pressure operated fresh water intake spray nozzle valve preferably employed.

Fig. 6 is a horizontal sectional view taken on the line 6—6 of Fig. 5.

Fig. 7 is a longitudinal sectional view taken on the line 7—7 of Fig. 1 showing a hydraulically operated rotary type scrubbing brush which may be employed advantageously with the invention.

Fig. 8 is a sectional view of the said hydraulic rotary brush taken on the line 8—8 of Fig. 7.

Fig. 9 is an enlarged vertical sectional view of the selective mixing control valve preferably employed, the fresh water valve element and the chemical valve element being shown in their "closed" position.

Fig. 10 is a bottom elevational view of the selective mixing control valve shown in Fig. 9.

2

Fig. 11 is a fragmentary sectional view similar to Fig. 9 showing the fresh water valve element of the selective mixing control valve 9 in its "open" position.

Fig. 12 is a fragmentary elevational view showing the means for holding the said fresh water valve element of the selective control valve "open."

Fig. 13 is a top plan view with portions broken away taken on the line 13—13 of Fig. 9 showing the grooving of the top of the fresh water valve element valve stem guide nut to accommodate the positioning pin employed to maintain the fresh water valve element "open" or "closed."

Referring now to the drawing wherein like numerals refer to like and corresponding parts throughout the several views, the particular embodiment of the chemical mixing and dispensing unit disclosed for the purpose of illustrating the invention comprises, in general, a portable pressure tank 20 connected to a pressure fresh water supply such as a hose bib 21 by a suitable hose 22, a fresh water line 23 extending laterally through the tank 20, a chemical flow line 24 beginning at a point within the tank 20 near the bottom thereof, running vertically within the tank 20 near the side thereof opposite the side where the said fresh water line 23 enters the said tank 20, and extending out the side of the tank 20 adjacent the point where the said fresh water line 23 leaves the tank, a pressure operated fresh water intake spray nozzle valve 25 disposed in the fresh water line 23 within the tank 20 at the side of the said tank 20 adjacent the side where the said fresh water line 23 enters the said tank 20, the said tank 20 including an open collar 26 at the top thereof providing a chemical filler opening, a cap 27 over the said collar, a pair of apertured cap anchor arms 28 extending upwardly from the said collar, a yoke 29 disposable through the said apertured cap anchor arms 28, and an anchorage screw 30 threaded through the said yoke engaging the cap 27 pressure sealing the cap 27 over the open collar 26 of the said tank 20, a removable reticulated chemical container 31 for soap, detergent and other chemicals disposed in the said collar 26 with a portion thereof extending down into the said tank 20 in range of spray emitted from the fresh water intake spray nozzle 25, a selective mixing control valve 32, a fresh water hose 33 and a chemical hose 34 connecting the fresh water line 23 and chemical flow line 24 respectively to the said selective mixing control valve 32, a hydraulic brush 35, and a selected mixture discharge line 36 con-

tinuing from the selective mixing control valve 32, a hydraulic brush 35, and a selected mixture discharge line 36 con-

tinuing from the selective mixing control valve 32, a hydraulic brush 35, and a selected mixture discharge line 36 con-

tinuing from the selective mixing control valve 32, a hydraulic brush 35, and a selected mixture discharge line 36 con-

tinuing from the selective mixing control valve 32, a hydraulic brush 35, and a selected mixture discharge line 36 con-

tinuing from the selective mixing control valve 32, a hydraulic brush 35, and a selected mixture discharge line 36 con-

tinuing from the selective mixing control valve 32, a hydraulic brush 35, and a selected mixture discharge line 36 con-

necting the selective mixing control valve 32 to the said hydraulic brush 35. The said pressure tank 20 is preferably provided with a clean-out aperture 31 at the bottom thereof plugged by a suitable drain plug 370. On large units where the pressure tank 20 is heavy, rubber tired wheels 38 are preferably provided near the rear thereof and a suitable foot 39 is provided at the front thereof. A handle 40 is extending upwardly from the back of the pressure tank 20 including a hand grip 41 on the upper end thereof of is provided as an aid to mobility of the unit.

The pressure operated fresh water intake spray nozzle valve 25 is disposed in the fresh water line 23 within the pressure tank 20 by means of a T-fitting 42 which has its branch 420 upwardly projecting as best indicated in Figs. 4 and 5. The fresh water intake spray nozzle valve 25 serves both as a spray nozzle and as a pressure valve which closes when pressure within the pressure tank 20 is sufficient to overcome the water pressure in the fresh water line 23. The said fresh water intake spray nozzle valve 25 comprises a sleeve 43 interiorly threaded at 430 to fit onto the upwardly disposed branch 420 of the T-fitting 42 and interiorly threaded at 4300 to receive a nozzle cap 44. The said sleeve 43 is provided with a horizontal portion 45 located between its interiorly threaded ends which is provided with a central aperture 46 and is beveled around the top of the said central aperture 46 to provide a valve seat 47 for the gravity valve member 48. The gravity valve member 48 is formed with a hex body 49, a beveled valve portion 50 which seats on the valve seat 47, and an upwardly disposed solid stem 51. The nozzle cap 44 is threaded at 460 to assemble into the upper threaded end 4300 of the sleeve 43 and is annularly cupped at 52 to receive in slidably telescoping relationship the hex body 49 of the gravity valve member 48. The nozzle cap 44 is also provided with an upwardly extending sleeve nozzle 53 communicating with the annular cup 52 thereof, into which sleeve 53 the upwardly disposed solid stem 51 of the valve member 48 loosely telescopes. Before assembling the pressure operated fresh water spray nozzle 25, a twisted slightly open ring 54 is positioned loosely around the solid stem 51 of the valve member 48. This permits water from the fresh water line 23 to pass through the spray nozzle 25 when the gravity valve member 48 is lifted by water pressure from the fresh water line 23, which water passes from the sleeve nozzle 53 and strikes the interior of the top of the tank 20 whereupon a portion of the fresh water strikes the reticulated chemical container 31 and dissolves a portion of the soap, detergent or other soluble chemical therein.

Any type of hydraulic brush 35 may be used, either stationary or rotary. In some cleaning operations a hydraulic brush having a rotating element therein is preferred. Such a rotary hydraulic brush is illustrated in Figs. 1, 7 and 8, and, not being a part of this invention except as an operating element, the said rotary hydraulic brush will not be described in detail except that it comprises a hollow handle 55 connected to the selected mixture discharge line 36 through which clear water from the fresh water line 23 or a selected solution from the pressure tank 20 or a mixture thereof passes to the brush head 56 into which is rotatably mounted a water turbine wheel 57 from whence clear water or selected solution or a mixture thereof escapes to the turbine brush 58 through 75

the clearance between the turbine wheel 57 and the brush head 56. The periphery of the brush head 56 is covered uniformly with suitable bristles 58 while the turbine wheel 57 is provided with a tufted bristle brush 59. Any type of a hydraulic brush 35 may be employed when the chemical mixing and dispensing unit is employed for cleaning purposes, and, when the unit is used as a sprayer, a suitable spray nozzle is substituted for the said hydraulic brush 35.

The selective mixing control valve 32 shown in Figs. 9-11 inclusive comprises a housing 60 having an upper horizontal fresh water intake port 61 to which the fresh water hose 33 is connected, a lower horizontal chemical intake port 62 to which the chemical hose 34 is connected, and a horizontal discharge port 63 to which the selected mixture discharge line 36 is connected. The fresh water intake port 61 communicates with an upper fresh water valve chamber 65 and the chemical intake port 62 communicates with a lower chemical valve chamber 66, which chambers 65 and 66 are connected to a fresh water passage 67 and chemical passage 68 respectively which are normally closed by spring loaded valves 69 and 70 respectively. The said fresh water passage 67 and the chemical passage 68 communicate with a mixing chamber 64 which leads to the said horizontal discharge port 63 to which the said selected mixture discharge line 36 is connected. The spring loaded valves 69 and 70 are preferably cylindrical in shape, seat on neoprene or other type seats 690 and 700, and are each provided with a stem 71 and 72 respectively which are reciprocatingly mounted in vertically and axially bored guide nuts 73 and 74 threaded in the top and bottom respectively of the housing 60. Each of the said valve stems 69 and 70 are provided with an annular groove 75 to accommodate an O-ring 76 which serves as packing between the said valve stems 71 and 72 and the guide nuts 73 and 74 respectively. Compression springs 77 and 78 disposed around the stem 71 and 72 respectively of each of the valves 69 and 70 react against the guide nut 73 and 74 respectively.

The fresh water control valve 69 has a knurled operating knob 79 fixed on its stem 71 by means of a suitable pin 80. A valve control pin 81 is disposed through and extends from both sides of the valve stem 71 in spaced relationship below the said knurled operating knob 79, which valve control pin is disposed in the deep transverse groove 82 in the top 83 of the guide nut 73, see Fig. 13. When it is desired to open the fresh water control valve 69, the knurled operating knob 79 is pulled out and rotated 90 degrees in either direction and released, whereupon the valve control pin 81 seats in the V-groove 84 provided therefor as best shown in Figs. 11 and 12. In this latter described position of the operating knob 79 of the fresh water control valve 69, the said valve 69 is unseated and fresh water passes from the fresh water hose 33, through the fresh water intake port 61, through the fresh water valve chamber 65, through the fresh water passage 67, through the mixing chamber 64 and out the discharge port 63 into the selected mixture discharge line 36.

The bottom of housing 60 of the selective mixing control valve 32 is provided with a lug 600 onto which a chemical control valve operating lever 85 is pivotally mounted on a pivot 86 extending through the said lug 600 of the housing 60 and through spaced lugs 87 provided on the chemical control valve operating lever 85 near

the inner end thereof. The outer end of the stem 72 of the chemical control valve 70 is pinned connected to the inner end of the chemical control valve operating lever 85 by means of a pin 88 extending through the said stem 72 of the chemical control valve 70 and a pair of spaced lugs 89 located at the inner end of the said chemical control valve operating lever 85. With this construction, the pressing of the outer end of the chemical control valve operating lever 85 opens the chemical control valve 70 and causes chemicals from the pressure tank 20 to pass through the chemical flow line 24, through the chemical hose 34, through the chemical intake port 62, through the chemical valve chamber 66, through the chemical passage 68, through the mixing chamber 64, and out the discharge port 63 into the selected mixture discharge line 36. The chemical control valve operating lever 85 is so arranged that it can be readily manipulated by the same hand that holds the hose-lines 33 and 34 and the selective mixing control valve 32, thus leaving the other hand of the operator free to handle the brush 35 or any implement substituted therefor.

Obviously, when only fresh water is required or desired, the fresh water control valve 69 is opened by manipulating the fresh water control valve operating knob 79. Also, when only chemicals are required or desired, the chemical control valve 70 is opened by manipulating the chemical control valve operating lever 85. In the case of chemicals, the chemical control valve 70 can be opened to a minute degree, or can be fully opened, or can be opened to any degree desired. By opening the fresh water control valve 69 and manipulating the chemical control valve 70 to the degree of opening desired, any combination or strength of solution can be obtained from pure water to a concentrated aqueous solution of chemicals.

Therefore, and as only one example of the operation of the invention, in washing an automobile, the reticulated chemical container 31 is filled with a powdered soap and a soapy solution can be obtained by opening the chemical control valve 70 only. A pure rinse water can be obtained by opening the fresh water control valve 69 only. A diluted solution of completely mixed and dispersed soap and water can be had by opening both the fresh water control valve 69 and the chemical control valve 70. If a weaker solution is required, the chemical control valve 70 is manipulated accordingly. The same situation is true when a detergent is employed rather than a soap. Likewise, a similar situation is true when chemical mixing and dispensing units embodying the invention are used as a sprayer or fertilizer spreader or for other purposes.

The invention is readily and effectively employed wherever and whenever a varied solution from a dissolvable crystalline or powdered chemical or soap is required alone or in alternation with clear water.

Although but a single embodiment of the invention has been disclosed and described in detail, it is obvious that many changes may be made in the size, shape, arrangement and detail of the various elements of the invention without departing from the spirit and scope thereof as defined by the appended claims.

We claim:

1. A chemical mixer comprising a pressure tank, a fresh water supply line extending through the said tank near the top thereof, a chemical flow line extending from the tank beginning at

15 a point within the tank near the bottom thereof, valve means for opening and closing the fresh water line and the chemical flow line independently of each other after they leave the tank, a reticulated chemical holder disposed in the tank at the top thereof, a fresh water intake nozzle valve disposed in the fresh water line within the tank closed responsive to air pressure built up within the tank and openable responsive to a drop of air pressure within the tank resulting from opening the chemical flow line from the tank, the said fresh water intake nozzle valve being located to spray fresh water on the reticulated chemical holder when chemical solution is being withdrawn from the said tank.

2. A chemical mixer comprising a pressure tank, a fresh water supply line extending laterally through the said tank near the top thereof, a chemical flow line extending from a point within the tank near the bottom thereof leaving the tank near the top thereof adjacent the point where the fresh water line leaves the tank, valve means for opening and closing the fresh water line and the chemical flow line independently of each other after they leave the tank, a reticulated chemical holder disposed within the said pressure tank above the said fresh water supply line, and a fresh water intake nozzle valve disposed in the said fresh water line within the tank adjacent the said reticulated chemical holder in spray relationship thereto normally open but automatically closable responsive to air pressure within the pressure tank created by the tank becoming filled with water and automatically openable responsive to a drop in air pressure within the pressure tank caused by the withdrawal of fluid through the chemical flow line.

3. A washer or spray comprising a pressure tank, a fresh water supply line extending through the said tank near the top thereof, a chemical flow line extending from the tank beginning at a point within the tank near the bottom thereof, a mixing valve hose connected to the fresh water supply line and hose connected to the chemical flow line including a mixture discharge hose leading therefrom, valve means within the said mixing valve for opening and closing the fresh water line and the chemical flow line independently of each other after they leave the tank, a reticulated chemical holder disposed in the tank at the top thereof, a fresh water intake nozzle valve disposed in the fresh water line within the tank closed responsive to air pressure built up within the tank and openable responsive to a drop of air pressure within the tank resulting from opening the chemical flow line from the tank, the said fresh water intake nozzle valve being located to spray fresh water on the reticulated chemical holder when chemical solution is being withdrawn from the said tank.

4. A chemical mixer comprising a pressure tank including an upwardly disposed collar and a closure means therefor, a fresh water supply line extending through the said tank near the top thereof, a chemical flow line extending from the tank beginning at a point within the tank near the bottom thereof, valve means for opening and closing the fresh water line and the chemical flow line independently of each other after they leave the tank, a reticulated chemical holder disposed in collar of the said tank and extending downwardly in the top thereof above the said fresh water line therethrough, a fresh water intake nozzle valve disposed in the fresh water line within the tank closed responsive to

air pressure built up within the tank and openable responsive to a drop of air pressure within the tank resulting from opening the chemical flow line from the tank, the said fresh water intake nozzle valve being located to spray fresh water on the reticulated chemical holder when chemical solution is being withdrawn from the said tank.

5. A washer or spray comprising a pressure tank including an upwardly disposed collar and a closure means therefor, a fresh water supply line extending through the said tank near the top thereof, a chemical flow line extending from the tank beginning at a point within the tank near the bottom thereof, a mixing valve hose connected to the fresh water supply line and hose connected to the chemical flow line including a mixture discharge hose leading therefrom, valve means within the said mixing valve for opening and closing the fresh water line and the chemical flow line independently of each other after they leave the tank, a reticulated chemical holder disposed in collar of the said tank and extending downwardly in the top thereof above the said fresh water line therethrough, a fresh water intake nozzle valve disposed in the fresh water line within the tank closed responsive to air pressure built up within the tank and openable responsive to a drop of air pressure within the tank resulting from opening the chemical flow line from the tank, the said fresh water intake nozzle valve being located to spray fresh water on the reticulated chemical holder when chemical solution is being withdrawn from the said tank.

6. A chemical mixer comprising a pressure tank, a fresh water supply line extending through the said tank near the top thereof, a chemical flow line extending from the tank beginning at a point within the tank near the bottom thereof, valve means for opening and closing the fresh water line and the chemical flow line independently of each other after they leave the tank, a reticulated chemical holder disposed in the tank at the top thereof, a fresh water intake nozzle valve disposed in the fresh water line within the tank closed responsive to air pressure built up within the tank and openable responsive to a drop of air pressure within the tank resulting from opening the chemical flow line from the tank, the said fresh water intake nozzle valve being located to spray fresh water on the reticulated chemical holder when chemical solution is being withdrawn from the said tank, the said fresh water intake nozzle valve consisting of a housing having a central aperture therein formed around said central aperture to provide a gravity valve seat, a nozzle cap over the said housing including an upwardly extending sleeve forming a nozzle, a gravity valve member within the said housing and nozzle cap having a stem telescoping loosely within the said upwardly extending sleeve and including a valve portion which seats on the said gravity valve seat, and an open twisted washer disposed around the said stem of the gravity valve member whereby to admit of the passage of fresh water through the nozzle cap when the fresh water intake nozzle valve is open responsive to a drop of air pressure within the said tank.

7. A chemical mixer comprising a pressure tank, a fresh water supply line extending laterally through the said tank near the top thereof, a chemical flow line extending from a point within the tank near the bottom thereof leav-

ing the tank near the top thereof adjacent the point where the fresh water line leaves the tank, valve means for selectively opening and closing the fresh water line and the chemical flow line independently of each other after they leave the tank, means for maintaining the said fresh water valve means open, the valve means for opening and closing the said chemical flow line being spring loaded in its closed position and operable only manually to the extent and duration required, a reticulated chemical holder disposed within the said pressure tank above the said fresh water supply line, and a fresh water intake nozzle valve disposed in the said fresh water line within the tank adjacent the said reticulated chemical holder normally open but automatically closable responsive to air pressure within the pressure tank created by the tank becoming filled with water and automatically openable responsive to a drop in air pressure within the pressure tank caused by the withdrawal of fluid through the chemical flow line.

8. A washer or spray comprising a pressure tank, a fresh water supply line extending through the said tank near the top thereof, a chemical flow line extending from the tank beginning at a point within the tank near the bottom thereof, a mixing valve hose connected to the fresh water supply line and hose connected to the chemical flow line including a mixture discharge hose leading therefrom, valve means within the said mixing valve for opening and closing the fresh water line and the chemical flow line independently of each other after they leave the tank, means for maintaining the said fresh water valve means open, the valve means for opening and closing the said chemical flow line being spring loaded in its closed position and operable only manually to the extent and duration required, a reticulated chemical holder disposed in the tank at the top thereof, a fresh water intake nozzle valve disposed in the fresh water line within the tank closed responsive to air pressure built up within the tank and openable responsive to a drop of air pressure within the tank resulting from opening the chemical flow line from the tank, the said fresh water intake nozzle valve being located to spray fresh water on the reticulated chemical holder when chemical solution is being withdrawn from the said tank, the said fresh water intake nozzle valve consisting of a housing having a central aperture therein formed around said central aperture to provide a gravity valve seat, a nozzle cap over the said housing including an upwardly extending sleeve forming a nozzle, a gravity valve member within the said housing and nozzle cap having a stem telescoping loosely within the said upwardly extending sleeve and including a valve portion which seats on the said gravity valve seat, and an open twisted washer disposed around the said stem of the gravity valve member whereby to admit of the passage of fresh water through the nozzle cap when the fresh water intake nozzle valve is open responsive to a drop of air pressure within the said tank.

9. A chemical mixer comprising a pressure tank, including an upwardly disposed collar and a closure means therefor, a fresh water supply line extending through the said tank near the top thereof, a chemical flow line extending from the tank beginning at a point within the tank near the bottom thereof, valve means for opening and closing the fresh water line and the

chemical flow line independently of each other after they leave the tank, means for maintaining the said fresh water valve means open, the valve means for opening and closing the said chemical flow line being spring loaded in its closed position and operable only manually to the extent and duration required, a reticulated chemical holder disposed in collar of the said tank and extending downwardly in the top thereof above the said fresh water line therethrough, a fresh water intake nozzle valve disposed in the fresh water line within the tank closed responsive to air pressure built up within the tank and operable responsive to a drop of air pressure within the tank resulting from opening the chemical flow line from the tank, the said fresh water intake nozzle valve being located to spray fresh water on the reticulated chemical holder when chemical solution is being withdrawn from the said tank.

10. A washer or spray comprising a pressure tank, including an upwardly disposed collar and a closure means therefor, a fresh water supply line extending through the said tank near the top thereof, a chemical flow line extending from the tank beginning at a point within the tank near the bottom thereof, a mixing valve hose connected to the fresh water supply line and hose connected to the chemical flow line including a mixture discharge hose leading therefrom, valve means within the said mixing valve for opening and closing the fresh water line and the chemical flow line independently of each other after they leave the tank, means for maintaining the said fresh water valve means open, the valve means for opening and closing the said chemical flow line being spring loaded in its closed position and operable only manually to the extent and duration required, a reticulated chemical holder disposed in collar of the said tank and extending downwardly in the top thereof above the said fresh water line therethrough, a fresh water intake nozzle valve dis-

posed in the fresh water line within the tank closed responsive to air pressure built up within the tank and openable responsive to a drop of air pressure within the tank resulting from opening the chemical flow line from the tank, the said fresh water intake nozzle valve being located to spray fresh water on the reticulated chemical holder when chemical solution is being withdrawn from the said tank, the said fresh water intake nozzle valve consisting of a housing having a central aperture therein formed around said central aperture to provide a gravity valve seat, a nozzle cap over the said housing including an upwardly extending sleeve forming a nozzle, a gravity valve member within the said housing and nozzle cap having a stem telescoping loosely within the said upwardly extending sleeve and including a valve portion which seats on the said gravity valve seat, and an open twisted washer disposed around the said stem of the gravity valve member whereby to admit of the passage of fresh water through the nozzle cap when the fresh water intake nozzle valve is open responsive to a drop of air pressure within the said tank.
